(57) **CLAIM**

The ornamental design for a flashlight, as shown and described.

DESCRIPTION

FIG. 1 is a top, front perspective view of the flashlight of the present invention;

FIG. 2 is a top rear perspective view thereof;

FIG. 3 is a top plan view thereof;

FIG. 4 is a bottom view thereof;

FIG. 5 is a side elevational view thereof;

FIG. 6 is a side elevational view thereof, showing the opposite side of FIG. 5;

FIG. 7 is a front elevational view thereof; and,

FIG. 8 is a rear elevational view thereof.

The broken line showing is for illustrative purposes only and forms no part of the claimed design.
